(57) CLAIM

We claim the ornamental design for a stapler, as shown and described.

DESCRIPTION

FIG. 1 is a right-side perspective view of a stapler

FIG. 2 is a left-side perspective view thereof;

FIG. 3 is a left-side perspective view thereof;

FIG. 4 is a left side view thereof;

FIG. 5 is a front view thereof;

FIG. 6 is a top view thereof; and,

FIG. 7 is a rear view thereof.

The portions of the stapler shown in broken lines are for illustrative purposes only and form no part of the claimed design.
